UNITED STATES PATENT OFFICE

WILLIAM A. JONES, OF WEST NEW BRIGHTON, NEW YORK, ASSIGNOR TO THE BAB-COCK & WILCOX COMPANY, OF BAYONNE, NEW JERSEY, A CORPORATION OF NEW JERSEY

SEAL FOR HEADERS

Application filed April 20, 1926. Serial No. 103,211.

My invention more particularly relates to the first of which, in the embodiment illustrated, is straight as it engages the plain side of the header 111, while the other flange 20 is stepped to conform to the stepped side of the header 111. The flanges 19 and 20 preferably engage grooves 21, 22 formed in the wall 15 (and 16) of the setting, and when the headers are vertical, as illustrated, the grooves in the wall of the setting will, of course, also be vertical. Suitable packing 23 and 24 is preferably interposed between the blocks 17 and the header and the wall of the setting between the flanges 19 and 20, respectively.

5 My invention will best be understood by reference to the accompanying drawings in which Fig. 1 is an elevation of a steam boiler and its setting partially broken away and in section to illustrate the headers and the 10 parts associated therewith; Fig. 2 is a fragmentary sectional view, partly in elevation, illustrating a nest of headers and the sealing means located between the end headers and the walls of the setting; Fig. 3 is a 15 fragmentary elevation, partly in section, of a header and a sealing block associated therewith; Fig. 4 is a side view of Fig. 3, and Fig. 5 is a sectional view taken on the line 5—5 of Fig. 3.

20 Like reference characters indicate like parts in the various views.

I have illustrated one embodiment of my invention in a steam boiler comprising a steam and water drum 10 and sinuous headers indicated generally at 11 and comprising an upper group or nest of headers 114 and a lower group or nest 115 connected together by nipples 113, it being understood that the headers are connected to headers at the other 25 side of the setting by boiler tubes, two of which are illustrated in Fig. 4 at 14, the headers being connected to the steam and water drum by connections not illustrated. The headers are provided with the usual 30 handhole fittings 112. The headers and tubes are located in a flue, two opposite walls of which are indicated at 15 and 16, sinuous sides of the end headers 111 facing the associated walls 15 and 16.

35 40 The space between the end headers and the associated wall is sealed by means comprising blocks 17 which are preferably formed of cast iron or other metal and having on the side facing the header the same contour as the facing side of the header itself, there 45 preferably being one block to each depression 113 in the header, the block being formed with a convex portion 18 engaging the said depression. The edges of each block are also 50 preferably provided with flanges 19 and 20,

The lowermost block associated with one of the headers 111 is preferably supported, and, in the embodiment illustrated, is supported on a lug 25 which is secured to the header itself, preferably by being welded thereto. Each of the remaining blocks is 65 supported by the block immediately beneath the same, so that the blocks are all carried by the lug 25 and moved upwardly and downwardly with the movement of the header under expansion and contraction of the latter. During such movement the flanges 19 and 20 of the blocks slide within the grooves 21 and 22, thereby maintaining the seal between the end headers and the associated wall and preventing leakage of gases through the space 80 between the header and wall.

I claim:

1. In combination, a wall, a header provided with a sinuous side facing towards said wall, and blocks, one for each depression of the header, the blocks having one side substantially conforming in contour to the facing portion of the sinuous side of said header and the opposite sides slidably engaging said wall, each block being provided 85 at the edge of said side with flanges overlapping the edges of said header.

2. In combination, a wall, a header provided with a sinuous side facing towards said wall, and blocks, one for each depression of the header, the blocks having one side substantially conforming in contour to the facing portion of the sinuous side of said header and the opposite sides slidably engaging said wall, said wall being provided with at least 95 100

one groove, said blocks having a portion engageable with and slideable within said groove.

3. In combination, a wall, a header provided with a sinuous side facing towards said wall, and blocks, one for each depression of the header, the blocks having one side substantially conforming in contour to the facing portion of the sinuous side of said header and the opposite sides slidably engaging said wall, said wall being provided with two spaced grooves, and said blocks being formed with projections engaging and slideable in the respective grooves of said wall.

4. In combination, a wall, a header provided with a sinuous side with a plurality of depressions facing towards said wall, blocks, one for each depression of the header, the blocks having one side substantially conforming in contour to the facing portion of the sinuous side of said header and the opposite sides slidably engaging said wall, and a support for the lowermost block, each of said blocks having an upwardly presented face in sealing and supporting engagement with its super-jacent block.

5. In combination, a wall, a header provided with a sinuous side facing towards said wall, blocks, one for each depression of the header, the blocks having one side substantially conforming in contour to the facing portion of the sinuous side of said header and the opposite sides slidably engaging said wall, and a support welded to the header for the lowermost block, each of the remaining blocks being supported on the block beneath it.

6. In combination, a wall, a header provided with a sinuous side with a plurality of depressions facing towards said wall, blocks each having one side substantially conforming in contour to the facing portion of the sinuous side of said header and the opposite sides slidably engaging said wall, and a support secured to the header for the lowermost of said blocks, each of said blocks having an upwardly presented face in sealing and supporting engagement with its super-jacent block.

7. In combination, a wall, a header provided with a sinuous side with a plurality of depressions facing towards said wall, blocks, one for each depression of the header, the blocks having one side substantially conforming in contour to the facing portion of the sinuous side of said header and the opposite side slidably engaging said wall, and a support secured to the header for the lowermost block, each of said blocks having an upwardly presented face in sealing and supporting engagement with its super-jacent block.

8. In combination, a wall, a header provided with a depression facing towards said wall, a block having a side substantially con-

forming in contour to the facing portion of the depression in said header and the opposite side slideable relatively to said wall, and means forming a groove and tongue engagement between said wall and said block.

WILLIAM A. JONES.
